CLAIM

The ornamental design for a locking pin for an excavator wear assembly, as shown and described.

DESCRIPTION

FIG. 1 is a top view of a locking pin for an excavator wear assembly showing my new design;

FIG. 2 is a left side view thereof;

FIG. 3 is a front view thereof;

FIG. 4 is a right side view thereof;

FIG. 5 is a rear view thereof;

FIG. 6 is a front perspective view thereof;

FIG. 7 is a bottom view thereof;

FIG. 8 is an exploded left side view thereof

FIG. 9 is an exploded perspective (lower) view thereof; and,

FIG. 10 is an exploded perspective (upper) view thereof.
